CLAIM

The ornamental design for an automobile tire, as shown and described.

DESCRIPTION

FIG. 1 is a perspective view of an automobile tire showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is an enlarged perspective view of a portion defined by lines 8-8 shown in FIG. 1; and,

FIG. 9 is an enlarged front view of a portion defined by lines 9-9 shown in FIG. 2.

The broken lines shown are included for the purpose of illustrating the unclaimed portions of the automobile tire and form no part of the claimed design.
